UNITED STATES PATENT OFFICE.

ADAM DOBSON, OF BELFAST, IRELAND.

PISTON-VALVE RING.

SPECIFICATION forming part of Letters Patent No. 732,837, dated July 7, 1903.

Application filed May 10, 1902. Serial No. 107,039. (No model.)

To all whom it may concern:

Be it known that I, ADAM DOBSON, engineer, a subject of the King of Great Britain and Ireland, residing at 27 Botanic avenue, in the city of Belfast, Ireland, have invented certain new and useful Improvements in Piston-Valve Rings and Piston-Rings, (for which I have obtained Letters Patent of Great Britain and Ireland aforesaid, dated October 28, 1901, and numbered 21,578;) and I do hereby declare the following to be a full, clear, and exact description of my invention, such as will enable others skilled in the art to which it appertains to make and use the same, reference being had to the accompanying drawings, and to the letters of reference marked thereon, which form a part of this specification.

My invention relates to the construction and arrangement of the piston-valve rings and piston-rings of a steam-engine; and it consists in the use of a slit ring having a lug or projection formed on the inside thereof at each side of the slit, which lugs or projections engage in a groove or slot in the body of the piston-valve or piston, whereby the valve-ring or piston-ring can be adjusted so as to prevent undue pressure against the sides of the valve-chamber or cylinder, while the valve-ring or piston-ring by means of the slit adjusts itself automatically to any taper in the barrel of the valve-chamber or cylinder. The ring is held against the steam-tight face of the valve by a wave-spring or other springs.

In order that my invention may be fully understood, I shall now proceed to refer to the sheet of drawings hereunto annexed, the same letters of reference indicating the same or corresponding parts of my improvements on both figures thereon.

Figure I is an elevation, partly in section, of a piston-valve, showing the slit ring at top, with the body of the valve indicated by dotted lines, and the ring at bottom having a lug or projection at each side of the slit, the body

of the valve with a groove or slot, the flange of the valve, and a wave-spring and tongue-piece to hold the ring in position, all in section; and Fig. II is a plan, partly in section, showing the slit ring with lugs or projections engaged in a groove or slot formed in the body of the valve.

a is the ring, arranged with a slit *b* and with lugs or projections *a' a'*.

c is the body of the valve, provided with a groove or slot *c'*, the end walls of which engage the lugs or projections *a' a'*.

d is a wave-spring.

e is a tongue-piece, and *f* is the steam-tight flange of the valve, carrying the valve and piston-valve ring.

The end walls of the slot *c'* by their engagement with the lugs *a' a'* prevent undue expansion of the ring *a*, and so prevents undue pressure upon the sides of the cylinder. The slit *b*, however, permits a limited contraction of the ring *a*, which therefore can automatically adjust itself to any slight inequalities on the surface of the cylinder-walls.

Having now particularly described and ascertained the nature of my said invention and in what manner the same is to be performed, I declare that what I claim is—

The combination of a piston having a slot in the body thereof, and a slit ring having separated lugs rigid therewith one on each side of the slit to project into said slot and engage the end walls thereof when the ring is expanded, and said slot permitting the ends of the slit ring and the lugs to approach each other, substantially as and for the purpose specified.

In testimony whereof I have signed my name to this specification in the presence of two subscribing witnesses.

ADAM DOBSON.
